ADJUSTING APPARATUS

Donald T. Robb, Downers Grove, Ill., assignor to
 Western Electric Company, Incorporated, New
 York, N. Y., a corporation of New York

Application October 10, 1942, Serial No. 461,624

10 Claims. (Cl. 153—48)

This invention relates to adjusting apparatus and more particularly to apparatus for adjusting the tension of contact springs.

It is an object of the present invention to provide an automatic apparatus for accurately and expeditiously adjusting an adjustable article.

In accordance with one embodiment of the invention, an apparatus is provided for repeatedly applying pressure to the end of a contact wiper spring when necessary to bend the spring to a position where it will exert the proper pressure on the contacts with which it is designed to cooperate. The springs are normally bent, in the manufacture thereof, to a position where they will apply more than the desired pressure on their associated contacts and in the present apparatus they will, if necessary, be bent in the opposite direction to correct this condition. Before and after each bending operation, the tension of the springs is tested and circuits are established for sorting the springs into three groups, depending upon whether they have the correct tension, more than the desired tension or less than the desired tension.

A better understanding of the invention may be had by reference to the following detailed description when considered in conjunction with the accompanying drawings, wherein

Fig. 1 is a plan view of an adjusting apparatus for adjusting contact wiper springs in accordance with the present invention;

Fig. 2 is a vertical sectional view taken substantially along the line 2—2 of Fig. 1 in the direction of the arrows showing a part of the adjusting mechanism and a part of the ejecting mechanism in elevation;

Fig. 3 is a fragmentary detail sectional view of a portion of the apparatus at the ejecting or delivery station showing the mechanism whereby the springs will be directed to one of the three containers;

Figs. 4, 5 and 6 are transverse vertical sectional views taken substantially along the lines 4—4, 5—5 and 6—6, respectively, of Fig. 1 in the direction of the arrows, Fig. 4 showing details of the adjusting mechanism, Fig. 5 showing portions of the drive mechanism for clamping the springs at the adjusting station, and Fig. 6 showing portions of the details for applying pressure to the springs to test them together with a part of the drive mechanism which controls the electrical circuits of the apparatus;

Fig. 7 is an enlarged fragmentary plan sectional view taken substantially along the line 7—7 of Fig. 2 in the direction of the arrows

showing the spring in position to be adjusted and gaged;

Fig. 8 is a vertical sectional view taken substantially along the line 8—8 of Fig. 7 in the direction of the arrows showing the pressure applying means and the gaging means in detail;

Fig. 9 is an exploded view in perspective of a portion of the clamping and pressure applying means; and

Fig. 10 is a circuit diagram illustrating schematically the circuit connections and various portions of the electrical control apparatus for the machine.

Referring to the drawings, wherein like reference characters designate the same parts throughout the several views, particularly to Fig. 1, wherein the apparatus is shown mounted on a bench or table 15. The bench or table 15 has a casing 16 mounted on its upper surface, into which there extends a drive shaft 17 connected to any suitable source of power, such as the motor 18 shown diagrammatically in Fig. 10, and having a worm 19 mounted upon it in mesh with a worm gear 19. The worm gear 19 is fixed to a shaft 20, on which there is, in turn, fastened a beveled gear 21 in mesh with a cooperating beveled gear 22 (Fig. 2) is mounted on the upper end of a stud shaft 23 journalled in a block 24 suitably attached to the underside of the table 15. The lower end of the stud shaft 23 has mounted on it a lever 25, carrying at its free end a cam roller 26, which is adapted to engage with and drive intermittently a slotted plate 27. The plate 27 is in the form of a disc and is attached to a shaft 28, carrying at its upper end a work supporting table 29, which will be indexed step by step to carry springs 30 from a loading area, designated generally by the numeral 31, in succession to an adjusting and gaging station 32 and to a discharge station 34.

The springs 30, which are to be adjusted and gaged in the apparatus constituting the preferred embodiment of the present invention, comprise a substantially circular body portion 40, as shown in Fig. 9, having a central aperture 41 co-axial with a semi-circular slot 42. The body portion 40 has a projection 43 extending from it and a contact arm 44 extending from it at mid-point of the semi-circular slot 42 so that the portion 50 of the spring which is to be flexed, in using the spring, starts at the ends of the slot 42 and extends to the opposite end of the contact spring.

The table 29 has positioned on it, adjacent its periphery, a series of mounting posts 45, which, as shown most clearly in Figs. 8 and 9, are pro-

vided with an upwardly extending projection 46 adapted to pass through the central aperture 41 in the spring 30 and to cooperate with an L-shaped spring 47 to hold a spring 30 to be adjusted and tested in place on the post during the indexing of the table 28. In order to insure that the springs 30 will be properly positioned at the gaging station, a spring pressed center stop 35 is provided for engaging the mounting posts 45 and centering them in position each time the table 28 is indexed. The upper end of the vertically disposed portion of the spring 47 is bifurcated to provide two tines 48 and 49 for bearing against the body portion 40 of the spring 30, the tine 49 extending up into a slot 50 formed by the cooperating surfaces of the body portion 40 and projection 43 of the spring 30. The springs 30 to be tested are placed on the posts 45 manually at the loading area 31 and then will be carried step by step around to the discharge station 34. In being carried around by the table 28, the springs will be tested and, if necessary, adjusted at the station 32 and then will be carried to the discharge station 34, where there is provided means for stripping the springs from the posts 45, as will be described hereinafter.

Within the casing 16, there are mounted a series of switches 55, 56, 57 and 58, which, together with a cam actuated switch 59 mounted on the outer surface of the casing 16, control the timing of various portions of the electrical apparatus to be described hereinafter. Switches 55, 56, 57 and 58 have associated with them cams 60, 61, 62 and 63, respectively, which control their operation, and the switch 59 is adapted to be actuated by a cam 74 mounted on the outer end of the shaft 20. The cams 60 to 63, inclusive, are mounted upon a cam shaft 64 journaled in the left wall (Fig. 1) of the casing 16 and in a bracket 65 extending into the casing 16. The shaft 64 carries a gear 66 in mesh with a gear 67 of the same size fixed to the shaft 20, whereby the cam shaft 64 is driven at the same speed as the shaft 20.

In addition to the switch actuating cam 74 and the gears 21 and 67, the shaft 20 carries a cam 68 having a series of nine raised portions 69 positioned about its periphery, as shown most clearly in Fig. 6. Cooperating with the cam 68 is a cam lever 70 (Fig. 6) pivoted in a bracket 71 fixed to the side wall of the casing 16. The free end of the lever 70 has a roller 75 rotatably mounted on it and normally engaged by a laterally extending projection 76 of a slide bar 77. The slide bar 77 is slidably mounted in a U-shaped bracket 78 fixed to the side wall of the casing 16 and has fixed to it adjacent its lower end a pin 79 for receiving the upper end of coil spring 80. The lower end of the coil spring 80 (Fig. 8) is attached to a lever 81 and is pivoted in a bracket 82 mounted on a base member 83, which is, in turn, mounted upon the table 15. Fixed to the underside of the left end (Fig. 8) of the lever 81 is an insulator 84, carrying an adjustable contact 85 in alignment with a contact 86 mounted on the underside of a U-shaped lever 87, which is also pivoted on the bracket 82. The upper portion of the U-shaped lever 87 has a spring 88 adjustably attached to it and the spring 88 has its lower end fixed to the lever 81 adjacent the left end thereof so that the spring 88 normally tends to hold the contacts 85 and 86 in engagement.

Adjacent the upper end of the base of the U-shaped lever 87, there is positioned a contact 89 for engaging an adjustable contact 90 mounted

in an insulator 91, which is, in turn, supported on a support member 92 extending upwardly from base member 83. The left end (Fig. 8) of the lower arm of the U-shaped lever 87 has attached thereto an irregularly shaped spring engaging hook 93, which is adapted to engage the extending contact arm 44 of the spring 30. If no spring is in position on the post 45 at the gaging station, there will be no resistance offered to the spring 88 holding the contacts 85 and 86 in engagement and, consequently, the spring 88 will rock the lever 81 counter-clockwise (Fig. 8) to disengage contact 89 from adjustable contact 90. However, if a spring 30 is in position on the post 45 at the gaging station and the slide bar 77 is moved upwardly and, through the spring 88, tends to pull the lever 81 counter-clockwise, the spring 88 will resist the movement of the hook 93. Thereafter, the strength of a spring 30 within predetermined limits will be determined by the relative time at which contacts 85 and 86 or contacts 89 and 90 open; that is, if contact 85 is moved away from contact 86 before contact 88 breaks with contact 90, the tension stored in the spring 30 is more than the desired amount, whereas, if contact 89 moves out of engagement with the contact 90 before contact 88 disengages from contact 86, this will indicate that the tension in the spring 30 being tested is less than a predetermined amount. In this manner, the tension in the spring 30 may be determined within predetermined limits, as described more in detail in connection with the description of the operation of the apparatus and the circuit.

In order to properly engage the contact arm 44 of the spring 30 with the hook 93, there is provided, adjacent the gaging station 32, a cam bar 94 (Fig. 7) mounted on a bracket 95 for guiding the contact arm 44 under the hook 93. In addition to the cam bar 94, there is provided a cam bar 96 mounted on a bracket 97 for engaging the top of the contact arm 44 as the contact arm passes out from under the hook 93 so that there will be no tendency for the resiliency of the contact arm 44 to snap the spring 30 off of the post 45 as the spring moves out of the adjusting and gaging station.

In order to hold the spring 30 fixed on the post 45 at the gaging and adjusting station, there is provided a plunger 105 (Figs. 2 and 8) having a socket 106 formed in its lower end for receiving the projection 46 on the post 45 in alignment therewith. The plunger 105 is slidably mounted on the lower end of a reciprocable member 107, being mounted for limited movement within the member 107 and being normally urged downwardly by a compression spring 108 (Fig. 2) to a position where the upper surface of a slot 109 formed in the plunger 105 will engage with a retainer pin 110 fixed in the lower end of the member 107. Carried by the plunger 105 are a pair of locating pins 111 and 112 (Fig. 9) which enter into the slot 42 adjacent the ends thereof to prevent the spring 30 from turning with respect to the post 45 and plunger 105 while the spring 30 is in the gaging and adjusting position. The reciprocable member 107 is slidable in a bearing 113 fixed to a wall of the casing 116 and is normally urged upwardly by a compression spring 114, which is compressed between a shoulder 115 on the member 107 and an internal shoulder 116 in the bearing 113. It will be noted, by reference to Figs. 2 and 5, that the upper end of the reciprocable member 107 engages a roller 117

mounted on the left end (Fig. 5) of the lever 118. The lever 118 is carried on a pivot pin 119 fixed in the casing 16 and is free to oscillate about the pin 119. At its right end, the lever 118 carries a cam roller 120 in engagement with the upper end of a cam plunger 121 slideable in bearing 122 and carrying at its lower end a cam roller 123 in engagement with a cam 124. The cam 124 is mounted upon the cam shaft 64 and each time the cam shaft 64 is rotated through a complete cycle, the cam plunger 121 will be reciprocated and will impart reciprocation to the reciprocable member 107 to carry the plunger 105 down into gripping engagement with a spring 30 positioned upon the post 45, where the spring will be held during the testing and adjustment thereof.

Fixed in the plunger 105 (Figs. 2, 4 and 8) is an irregularly shaped pivot supporting member 130, to which there is attached a contractile spring 131, which is, in turn, connected to a sleeve 132 slideable with respect to the plunger 105. The sleeve 132 is urged to move upwardly by the spring 131 to carry a spring bending finger 133 up out of engagement with a spring 30 mounted upon the post 45 at the adjusting and gaging station 32. The sleeve 132 is provided with an annular shoulder 134 adapted to be engaged by the spaced fingers of a bifurcated member 135, which is fixed to a substantially vertically extending portion 136 of a bell crank lever 137. The bell crank lever 137 is oscillatable about a pivot pin 138, which is, in turn, fixed in the pivot supporting member 130. A plunger 139 is pivoted to the substantially horizontally extending arm of the bell crank 137 at 140 and is normally urged downwardly by a compression spring 141 (Fig. 2), which surrounds it, and engages a shoulder 142 fixed to plunger 139. The upper end of the spring 141 bears against a plate 143 mounted on the reciprocable member 107 and movable therewith. Thus, the plunger 139 is normally urged downwardly for moving the member 135 upwardly (Fig. 8).

Intermediate its ends, the plunger 139 has a pin 144 extending through it and into slots 145 formed in the forked end of a lever 146. The lever 146 has its opposite end pivoted on a shoulder 147 of a solenoid plunger 148. The solenoid plunger 148 is normally urged downwardly (Fig. 4) by a compression spring 149 interposed between the shoulder 147 and the bracket 150 to carry the shoulder 147 into engagement with a bracket 151, in which there is provided an aperture 152 for receiving a reduced portion 153 of the solenoid plunger 148 to guide the movement of the plunger. The plunger 148 is adapted to be actuated by a solenoid 154 suitably mounted on the casing 16 and when the solenoid 154 is not energized, the spring 149 will force the plunger 148 downwardly to position a camming projection 155 formed on the lever 146 into the path of a series of camming pins 156. The camming pins 156 are adjustably mounted about the periphery of a cam wheel 157 mounted upon the shaft 20 and each of them projects radially slightly beyond the preceding pin to impart successively greater amounts of movement to the parts which they actuate. Thus, when the solenoid 154 is not energized, the lever 146 will be rocked with respect to the plunger 148 and will raise the plunger 139, thereby to force the sleeve 132 downwardly and bend the spring 30 each time one of the camming pins 156 engages the camming projection 155. The spring 30 will be tested, as will be described in connection with the description

of the electrical circuit of the apparatus, in the interval between the engagement of the camming projection 155 by the various camming pins 156 and if the spring bending finger 133 has bent the spring 30 sufficiently to bring it within the acceptable range, the solenoid 154 will be energized to move the left end (Fig. 4) of the lever 146 upwardly, thereby to carry the camming projection 155 out of the path of the pins 156. After all of the camming pins 156 have moved past the camming projection 155, the table 29 will be indexed to carry the gaged and adjusted spring 30 out of the adjusting and gaging station 32 and move a new spring into position in the station 32.

As the springs 30 are gaged, circuits will be set up to determine into which of three classes an adjusted spring falls and a control circuit will be set up for controlling a pair of gates 165 and 166 at the discharge station 34 to determine whether the spring should be directed through a passage 167, a passage 168 or a passage 169 to suitable receptacles positioned beneath these passages.

At the discharge station 34, there is provided a chute 170, into which springs 30 are to be discharged for direction downwardly to either of the passages 167, 168 or 169. The chute 170 has its inner wall, i. e., the wall closest to the table 29, curved toward the posts 45, as shown at 171 and this wall of the chute 170 cooperates with a stationary cam 172 to cam a spring 30 off of the post 45 and into the chute 170. The cam 172 is mounted on a bent-over portion 173 of a bracket 174, which is, in turn, fixed to the upper end of the chute 170 in any suitable manner. Thus, the cam 172 and the curved portion 171 of the chute 170 will cooperate to strip a spring 30 off of the post 45 against the clamping action of the spring 47.

From the preceding description of the mechanical structure of the apparatus, it will be apparent that each time the table 29 is indexed, a post 45 carrying a spring 30 will be moved into vertical alignment with the plunger 105 and properly aligned therewith by means of the center stop 35. Then, while the spring 30 is in position under the plunger 105, the plunger will be moved downwardly to grip the spring due to the action of the cam 124 through cam plunger 121, lever 118 and reciprocable member 107 each time the shaft 64 rotates through one complete cycle. While a spring 30 is clamped in position to be gaged, and, if necessary, adjusted at the station 32, a gaging and adjusting cycle will take place through the action of cams 68 and camming pins 156 on their respective levers 70 and 146, the adjusting operations of the lever 146 being interrupted when a spring is properly adjusted due to the energization of the solenoid 154 under control of the electrical circuit, which will be described hereinafter.

The apparatus may be placed in condition for operation by closing switches 181, 182, 183 and 184 (Fig. 10). Closure of the switch 181 will supply current from 110 volt A. C. source 185 to motor 186, which drives the shaft 17. Closure of switch 182 will connect the 110 volt A. C. source across a signal lamp 187 to indicate that the main portion of the circuit is in condition to operate and also to a rectifier circuit 188 enclosed within dotted lines (Fig. 10) which rectifier circuit will supply current to operate three thermionic valves 189, 190 and 191. Closure of the switch 184 will connect the negative side of a battery 192 to cutout switch 59 and through lever

87, contacts 89 and 88, to contact 86 at the gaging and adjusting station. With the apparatus thus set up, the closure of switch 183 will connect battery at 194 to one side of the winding of an actuating electromagnet 195 of a telephone type stepper switch 196. The stepper switch 196 is provided with four arcuately disposed banks of contacts 197, 198, 199 and 200 having brushes 201, 202, 203 and 204, respectively, associated therewith. The circuit to the electromagnet 195 will be completed once in each cycle of rotation of shaft 64 by closure of switch 55 to step the brushes 201, 202, 203 and 204 into engagement with the next succeeding contact in the arcuately disposed bank of contacts 197 to 200, respectively, thereby to move the brushes 201, 202, 203 and 204 successively into engagement with all of the contacts on their respective banks. Each of the contacts in the bank 198 is connected to a condenser 220 individual thereto and each of the contacts in the bank 200 is connected to a condenser 221 individual thereto so that if battery is connected through either the brush 202 or the brush 204 when it is in engagement with one of its associated contacts, the condenser connected to that contact will be charged. The brushes 201 and 203 serve to interconnect the grid circuit of valves 191 and 190, respectively, with their associated contacts in the banks 197 and 199, respectively. The contacts of the bank 197 are interconnected with the contacts of the bank 198 serially so that when the brush 201 or 203 is in engagement with its first contact, it is also connected to the sixth contact on the bank 198 or 200. Similarly, all of the contacts of the bank 197 are interconnected with all of the contacts of the bank 198, but are displaced six contacts and the contacts of the bank 199 are interconnected with the contacts of the bank 200, being displaced six positions so that a charge put on a condenser associated with the contacts of bank 198 or bank 200 will be directed through the brushes 201 and 203 when the brush 201 or 203 has moved six places from the place at which the charge was applied to the condenser 220 or 221. In this manner, any charge applied to a condenser will be effective to trip the valves 190 or 191 with which it is connected by the brush 203 or 201 after the table 28 has indexed six places from the place at which the charge was applied to the condenser. The plate circuits of the valves 190 and 191 are connected to the winding of relays 204 and 205, respectively, and the other side of these windings is connected through switch 58 back to the rectifier circuit 188, near the end of the cycle of cam 63. Therefore, when a charge is applied to one of the condensers 220 or 221, as will be described herein-after, that charge will be removed from the condenser after the table steps six places and the charge on the condenser will be utilized to trip the valve 191 or the valve 190 and pull up relay 205 or relay 204, respectively. The relays 204 and 205, in closing their contacts, will complete circuits either to an electromagnet 206 or an electromagnet 207, this circuit being connected through the switch 183 and battery 194 to energize the electromagnets selectively at the time that a spring which had been gaged and adjusted at the gaging and adjusting station 72 reaches the discharge station 34.

The electromagnet 206 has its armature 208 pivoted at 209 (Fig. 3) and when the electromagnet 206 is energized, it will attract its armature 208, to which a link 210 is pivoted. The link 75

210 is interconnected to the armature 208 and a lever 211, which is normally urged to rock in a counter-clockwise direction by a contractile spring 212. The lever 211 is fixed to the gate 165 and, therefore, normally tends to hold the gate 165 in a vertical position (Fig. 3) to permit springs discharged into the chute 170 to pass straight down through the passage 168 to a receptacle for receiving properly adjusted springs. However, upon energization of the electromagnet 206, the gate 165 will be tilted to the position shown in dot and dash lines (Fig. 3) and will, accordingly, direct springs, which, when initially tested, did not have sufficient tension in them through the passage 167 to a receptacle (not shown) for receiving springs of this type. The electromagnet 207 has associated with it a gate actuating mechanism of exactly the same construction as that provided for the electromagnet 206 and when electromagnet 207 is energized, it will rock the gate 166 counter-clockwise to direct any springs 30 which, at the completion of an adjusting cycle, still has not the desired tension, from the chute 170 into the passageway 169 and from thence to a receptacle (not shown) for receiving springs having too much tension after the adjusting cycle is completed.

In testing the springs 30 to determine whether they have the proper amount of tension in them, the springs are moved under the hook 93 and the slide bar 77 is moved upwardly by the lever 70 and when this operation is performed, spring 30 will tend to rock lever 81 counter-clockwise. If the tension in the spring 30 being tested is too great, spring 30 will be stretched and contact between contacts 85 and 86 will be opened. Each time, in the cycle of operation, that the cam 68 raises the lever 70, cut-out switch 59 will be closed and the negative side of battery 192 will be applied to contacts 86 and 88 and through the switch 59 to contact 90. Therefore, if contact between contacts 85 and 86 opens before contact between contacts 88 and 90 opens, then none of the valves 189, 190 or 191 will be tripped and camming pin 156 will engage camming projection 155 on lever 146 to cause the spring bending finger 133 to be moved downwardly and bend the spring 30 to take a definite amount of tension out of it. As soon as the first camming pin 156 moves out of engagement with the camming projection 155, the circuits to the gage lever 81 will again be completed through switch 59 and the spring will be gaged. These gaging operations will continue until all of the camming pins 156 have passed under the camming projection 155 unless at some time during the portion of the cycle where the pins 156 are engaging the projection 155, the spring 30 is adjusted by the spring bending finger 133 to fall within the acceptable class.

If a spring under test is, as originally placed in the machine, too weak to be acceptable, the lever 81 will rock with the slide bar 77 and the first time the slide bar 77 moves upwardly, contact between contacts 88 and 90 will break before the contact between contacts 85 and 86 breaks and before the spring is bent by the spring bending finger 133. At this time in the cycle of operation of the apparatus, switch 57 is in the condition shown in Fig. 10 and, when contact between contacts 88 and 90 breaks while contact is still made between contacts 85 and 86, current from battery 192 will flow in a circuit through a resistance 212 and a resistance 213 in series, thus making point 214 more positive than point 215

and the grid of trigger tube 188 will be less negative with respect to its cathode, causing the tube to trip and supply power from its plate circuit through switch 57 to energize a relay 216. The relay 216, in pulling up, will supply battery from battery 194 through closed switch 183 and its make contact to energize the solenoid 154. When the solenoid 154 is energized, it will raise the left end (Fig. 4) of the lever 48 against the action of the spring 148 and, accordingly, will interrupt the operation of the camming pins 156 on the camming projection 155 of lever 146 and thus prevent the application of pressure tending to adjust the spring 30 in the gaging and adjusting station. Relay 216, in addition to connecting battery to operate the solenoid 154, will also connect battery at 194 through switch 183 and its break make contact to brush 202 to charge the condenser 203 associated with the contact in the bank 198 with which the brush is at that time in engagement.

The gaging operation just described will take place while the first raised portion of cam 74 is holding switch 59 closed and while switch 57 is in the condition shown in Fig. 10, and if the spring under test is stronger than desired, contact between contacts 85 and 86 will open before contact between the contacts 89 and 90 and, accordingly, resistance 213 will be cut out of the circuit of battery 192 and the valve 189 will not be tripped. Therefore, the next camming pin 156 will be permitted to engage the camming projection 155 due to the fact that the solenoid 154 will not be energized at this time.

As the disc 157 continues to rotate, the pins 156 will successively engage the camming projection 155 on the lever 146 and will continue to apply bending stresses to the spring 30 at the gaging and adjusting station until the spring is either properly adjusted or until all of the pins 156 have moved past the camming projection 155. If the spring being gaged and adjusted falls within the proper class before the disc 157 completes its cycle and carries the last camming pin 156 past the camming projection 155, the contact between contacts 89 and 90 will be broken before contact between contacts 85 and 86 is broken and the valve 189 will be tripped.

As soon as the first high portion of the cam 74 has passed under the switch 59 and the switch reopens after first being closed, switch 57 will be shifted to carry its make-break contact into engagement with its upper contact and, accordingly, the plate circuit of the valve 189 will then be connected to one side of the winding of a relay 217, the other side of the winding of which is connected to the rectifier 188. This will cause the relay 217 to be energized and shift its make-break contact if contacts 89 and 90 open before contacts 85 and 86. The make-break contact of relay 216, which is, at this time, deenergized, will supply current from battery 194, through switch 183, break-make contact of relay 216, make contact of relay 217, to the solenoid 154, thereby to stop the operation of the bending finger 133 by lifting the camming projection 155 on lever 146 out of the path of the camming pins 156. Since switch 56 is open at this time, no condenser 221 will be charged when a spring 30 is properly adjusted during the cycle of adjusting operations and no condenser 220 will be charged at this time since relay 216 is not operated at this time through switch 57. Thereafter, neither the gate 165 nor 166 will be operated six steps later in the cycle of the table 29.

If, after all of the camming pins 156 have passed under the camming projection 155, the spring 30 being adjusted does not have the proper tension, contact between contacts 85 and 86 will be opened while the last raised portion of cam 74 is holding switch 59 closed. At this same time, switch 56 will be closed by its cam 61 and switch 57 will be in its middle position engaging neither of its contacts. Therefore, neither relay 216 nor relay 217 will be energized and a circuit will be completed from the positive side of battery 194, through switch 183, break contacts of relays 216 and 217, through closed switch 256 and brush 204 to charge one of the condensers 221 whose associated contact is at that time engaged by the brush 204.

From the foregoing, it will be apparent that if, in the course of gaging a spring 30, the spring is properly adjusted, no condenser on the banks 198 or 200 will be charged, but, if the spring initially has less than the desired amount of tension stored in it, a condenser 220 will be charged before the first adjusting operation and solenoid 154 will be energized to prevent the bending finger 133 from bending the spring. If, after the adjusting cycle is completed, that is, the last of the camming pins 156 has engaged the camming projection 155, the spring under test is still too strong, a circuit will be completed to charge one of the condensers 221.

Since the discharge station 34 is six steps removed around the periphery of the table 29 from the gaging and adjusting station 32, the spring tested at the gaging and adjusting station and adjusted therein, if necessary, will have moved six steps before it is discharged into the chute 170 and, accordingly, any condenser 220 or 221 which was charged while a spring was being gaged and adjusted, will be connected through the banks of contacts 197 and 199 to the brush 201 or 203, respectively, to apply potential to the grid circuit of the valves 191 or 190, respectively, after six complete cycles of the shafts 20 and 64, the brushes 201, 202, 203, and 204 being stepped step by step into engagement with their associated contacts one step at a time after each gaging and adjusting operation due to the closure of switch 55 by cam 60. In this manner, those springs which are gaged and, if necessary, adjusted at station 32, will be directed through either passageway 167, 168 or 169, depending upon which of the three conditions existed when the spring was in the gaging and adjusting station and the tripping of either valve 190 or valve 191 will energize relay 204 or relay 205, respectively, to selectively energize electromagnet 206 or electromagnet 207, as was described hereinbefore.

What is claimed is:

1. An article adjusting apparatus comprising means for repeatedly testing the article to determine the quality thereof, means for making progressive adjustments in the article to impart said quality to it including means normally held in position to engage and adjust the article, and a solenoid responsive to said testing means and operable to remove the means normally engaging the article from contact with the article for interrupting the operation of the means for making progressive adjustments in the article when the article has said quality.
2. An article adjusting apparatus comprising means for repeatedly testing the article to determine the quality thereof, adjusting means for making progressive adjustments in the article to impart said quality to it, means responsive to said

testing means for interrupting the operation of the means for making progressive adjustments in the article when the article has said quality including a solenoid energizable to lift the adjusting means out of operative position, and means also under control of said testing means for sorting articles into classes depending upon whether they are properly adjusted or have more or less than the desired quality.

3. An article testing and adjusting apparatus comprising means for supporting an article in position to be tested, means for repeatedly testing the article while held in said position, means for making repeated adjustments to the article including an adjusting member and a pivoted lever for actuating said adjusting member, and means controlled by the testing means for interrupting operation of the adjusting means when the article is properly adjusted comprising means for normally supporting the pivoted lever in position to actuate the adjusting member, and means for shifting said last-mentioned means to render the pivoted lever inoperative.

4. A spring adjusting apparatus comprising leverage mechanism operable to bend a spring in successive increasing increments, a cam drum for actuating the leverage mechanism, a solenoid, means actuatable by said solenoid for pivotally supporting a part of the leverage mechanism in operative association with the cam drum when the solenoid is deenergized, means for testing the spring before each bending operation, and means controlled by the testing means for rendering the bending means ineffective to perform succeeding bending operations when a spring has a predetermined tension including means for energizing said solenoid.

5. In a spring adjusting apparatus, means for engaging a spring to bend it, means for actuating the spring engaging means in successively increasing amounts, a normally deenergized solenoid for normally holding the spring engaging means and its actuating means in operative relation, power means to deenergize the solenoid to interrupt operation of the engaging means by its actuating means, and a testing means for controlling said solenoid.

6. In a spring adjusting apparatus, an adjusting station and a discharge station, means for moving articles step by step past the adjusting station to the discharge station, means for testing articles in the adjusting station, means controlled by the testing means for adjusting articles in the adjusting station when necessary, means under control of the testing means for registering in which of three classes an article falls, and means operable after the article has been moved to the discharge station for directing the article to one of three places under control of the registering means.

7. In a spring adjusting apparatus, an adjusting station and a discharge station, means for

moving articles step by step past the adjusting station to the discharge station, means for testing articles in the adjusting station, means controlled by the testing means for adjusting articles when necessary, means under control of the testing means for registering in which of three classes an article falls, and means operable after the article has been moved to the discharge station for directing the article to one of three places under control of the registering means, said registering means including banks of condensers for receiving a charge while an article is being tested and for utilizing said charge when the articles are being sorted.

8. In a spring adjusting apparatus, an adjusting station and a discharge station, means for moving articles step by step past the adjusting station to the discharge station, means for testing articles in the adjusting station, means controlled by the testing means for adjusting articles when necessary, means under control of the testing means for registering in which of three classes an article falls, and means operable after the article has been moved to the discharge station for directing the article to one of three places under control of the registering means, said registering means including banks of condensers for receiving a charge while an article is being tested and for utilizing said charge when the articles are being sorted.

9. An article testing and adjusting apparatus comprising an article carrying means, means disposed in the path of said article carrying means for testing an article, means also in the path of an article on the carrying means for stripping the article therefrom, and means controlled by the testing means for sorting the articles when they are stripped from the carrying means, said sorting means including banks of condensers operable under control of the testing means when the article is in one position and dischargeable to control the sorting means when the article is in another position.

10. A spring adjusting and testing apparatus comprising an indexable table for carrying articles to a plurality of positions, means adjacent one position of said table for repeatedly testing and progressively adjusting a spring, means for moving said table step by step, a sorting means also adjacent another position of said table removed a number of steps from the testing and adjusting means, means responsive to the testing means for registering the result of testing operations on the spring, and means interconnecting the sorting means and registering means to control the sorting means in accordance with registrations made by the registering means under control of the testing means.
